CLAIM

The ornamental design for a case for an electronic device, as shown and described.

DESCRIPTION

FIG. 1 is a rear, left-side, and bottom perspective view of a case for an electronic device, showing our new design; FIG. 2 is a rear view thereof;

FIG. 3 is a front view thereof;

FIG. 4 is a right side view thereof;

FIG. 5 is a left side view thereof;

FIG. 6 is a top view thereof;

FIG. 7 is a bottom view thereof;

FIG. 8 is a front, right-side, and top perspective view thereof;

FIG. 9 is an enlarged detail view of the delineated region of FIG. 1;

FIG. 10 is an enlarged detail view of the delineated region of FIG. 2;

FIG. 11 is an enlarged detail view of the delineated region of FIG. 3; and,

FIG. 12 is an enlarged detail view of the delineated region of FIG. 5.

The dot-dash broken lines in FIGS. 1-3, 5, and 9-12 delineate regions of the case for an electronic device, including claimed subject matter, that are shown on an enlarged scale in FIGS. 9-12. The dashed broken lines depict portions of the case for an electronic device that form no part of the claimed design. The dot-dash and dashed broken lines form no part of the claimed design.
